UNITED STATES PATENT OFFICE

JOSEPH JACOBS, OF BRIDGEPORT, CONNECTICUT, ASSIGNOR TO THE A. J. DONAHUE CORPORATION, OF MILFORD, CONNECTICUT, A CORPORATION

DISPENSING-PACKAGE FOR POWDER PUFFS

Application filed April 30, 1932. Serial No. 608,482.

This invention relates to an improvement in dispensing-packages for powder puffs, the object being to provide a simple and attractive carton which may contain a stack of powder puffs, with an opening at the bottom through which the powder puffs may be removed, and a closure for said opening.

The invention consists in the construction as hereinafter described and particularly recited in the claims.

In the accompanying drawing:

Fig. 1 is a side view of a dispensing-package for powder puffs;

Fig. 2 is an under-side view of the same;

Fig. 3 is a vertical sectional view on an enlarged scale; and

Fig. 4 is a sectional view on the line 4—4 of Fig. 1, enlarged.

In carrying out my invention, I employ a carton 10, preferably square in cross-section and formed in the usual manner of knock-down cartons, the upper ends 11 and 12 being folded over to close the top.

At the other end, the sides of the cartons 25 are formed with short flaps 13 which will turn outward, and secured to the surface of a base 14, preferably rectangular to correspond to the design of the carton, and passed over the carton and also secured to the base 30 14 and to the upper surface of the flaps 13, is a retaining-plate 15.

The base is formed with a centrally-arranged circular opening 16, and secured to one corner of the base is a cover 17, and this 35 cover is scored as at 18, so as to form a hinge and permit the main portion of the cover to drop downward and expose the opening 16. The cover, base and plate are graduated in size so as to form a stepped bottom for the 40 carton.

Preferably one of the side corners of the carton will be cut away, forming a sight-opening 19, and this opening will be closed by a sheet 20 of cellophane or other suitable 45 transparent material, through which a stack of powder puffs 21 may be seen. The powder puffs are of usual construction, formed from soft material, and of a diameter slightly larger than the diameter of the opening 16.

The carton is filled with a stack of puffs

and preferably the upper end will be sealed. The device rests upon a dresser and when the user wishes a puff, it is only necessary to lift the device, which will allow the cover to drop downward as indicated by broken lines 55 in Fig. 3, and expose the lowermost puff which may be readily extracted with the fingers. Then, as the device is replaced on the dresser, the cover is closed. This device may be ornamented to any extent so as to provide an attractive addition to a dressing table, and provides a number of puffs which may be used as desired and which are protected until the last one is removed.

The carton, base, plate and cover are preferably formed from paper so that they can be produced at a low cost for manufacture and discarded when empty.

I claim:

1. A dispensing-package for powder puffs 70 comprising a casing with the lower ends turned outward, a base to which the outwardly-turned ends are secured, a centrally-arranged opening in the base, and a cover adapted to close said opening. 75

2. A dispensing-package for powder puffs comprising a casing adapted to contain a stack of powder puffs and closed at its upper end, said casing formed at its lower end with outwardly-extending flanges, a base to the top of which said flanges are secured, a plate also secured to said base and overlapping said flanges, said base formed with a central opening, and a cover hinged to said base. 80

3. A dispensing-package for powder puffs 85 comprising a casing adapted to contain a stack of powder puffs and closed at its upper end, said casing formed at its lower end with outwardly-extending flanges, a base to the top of which said flanges are secured, a plate 90 also secured to said base and overlapping said flanges, said base formed with a central opening, and a cover hinged to said base, one corner of the container cut away and the opening closed by a strip of transparent material. 95

In testimony whereof, I have signed this specification.

JOSEPH JACOBS.
